UNITED STATES PATENT OFFICE.

WILLIAM S. TROWBRIDGE, OF CHICAGO, ILLINOIS, ASSIGNOR TO AMERICAN STEEL
FOUNDRIES, OF NEW YORK, N. Y., A CORPORATION OF NEW JERSEY.

DRAFT-ARM.

1,181,358.

Specification of Letters Patent. Patented May 2, 1916.

Application filed November 29, 1915. Serial No. 63,933.

To all whom it may concern:

Be it known that I, WILLIAM S. TROWBRIDGE, a citizen of the United States, and resident of Chicago, in the county of Cook 5 and State of Illinois, have invented certain new and useful Improvements in Draft-Arms, of which the following is a specification.

My invention relates to car underframes, 0 and has particular reference to a novel sill-strengthening device for wooden center sill cars.

It has been found in practice that cars 5 constructed with wooden center sills are often damaged, due to the weakening or breaking of the center sills at a point contiguous to the body bolster. Many effective devices have been suggested with the object in view 0 of overcoming this difficulty, the present improvement, however, relating to a modification in which rolled metal shapes are utilized to a large extent, to the end that the cost of construction may be cheapened, and a construction provided in which the 5 effective resistance is secured in metal having the desired characteristics.

It is well understood that at points likely 0 to receive shocks and blows a cast metal of massive form is most effective, but that a construction including rolled metal beams is better adapted to resist bending strains without breaking. To this end the draft arm of my invention comprises a construction including cast and rolled shapes, all 5 riveted together to form a substantially integral structure.

The invention will be more readily understood by reference to the accompanying drawings, wherein—

0 Figure 1 is a side elevation of a draft arm constructed in accordance with my invention; Fig. 2 is a plan view of the same; Fig. 3 is a section on the line 3—3 of Fig. 2, and Fig. 4 is a section on the line 4—4 5 of Fig. 2.

Referring to the drawings, it will be seen that I have indicated, in Figs. 1 and 2, the sills 10 in dotted lines. The end sill is indicated at 11, and a sub-sill at 12. Extending 0 alongside the center sills and rigidly secured thereto by suitable bolts, are rolled metal beams in the form of bulb angles, these beams having a vertical web 13, and a horizontal web 14, the vertical web terminating 5 in a bulb 15. These beams extend from the

end sill 11 to a point a substantial distance to the rear of the body bolster. The body bolster is not shown, but is intended to occupy the space lettered 16 in the drawings. The beams are united at their forward end 60 by a transverse vertical web 17, at an intermediate point by the plate 18, and a point at the rear of the body bolster by a transverse angle 19, the vertical leg of which acts as an abutment for the sub-sill 12 and also 65 for the body bolster. The beam is suitably secured to the wooden center sills by means of transverse bolts located as shown in Fig. 1. Secured to the horizontal leg of the angles, as best shown in Figs. 1 and 3, are 70 draft rigging supporting plates 20 and 21, having thereon the usual stops against which the draft rigging followers may abut. To the upper edge of these plates is secured 75 an angle 22, which underlies the wooden center sills and may be suitably bolted thereto, as shown by the apertures 23 in Fig. 2. This rolled metal angle, as best shown in Fig. 1, extends forwardly to a point outside of the deadwood 24, being 80 stepped down, or deflected vertically, to accommodate the end sill 11 and the deadwood. The lower edges of the plates are likewise stiffened by a rolled metal angle 85 25, bent upwardly at the forward end into engagement with the end portion of the angle 22. The rolled metal shapes are securely riveted to the castings and become in effect an integral part thereof. The rear ends of the plates 20, 21 are united by the 90 cross plate 26, as best shown in Figs. 1 and 2.

It will be noted that when the parts are combined as shown and securely riveted together, that a substantially integral structure is produced in which the metal is 95 properly disposed to best withstand the shocks and strains of service.

I claim:

1. In a device of the class described, the combination of a pair of rolled metal beams 100 of angular cross section and extending rearwardly from the end sill and terminating at the rear of the body bolster, a pair of cast metal draft rigging cheek plates secured to the horizontal flanges of said beams, and a 105 rolled metal angle applied to the upper edge of each of said cheek plates, a horizontal leg of which angle is adapted to underlie a car center sill and to extend beneath the car end sill, substantially as described. 110

2. In a device of the class described, the combination of a pair of rolled metal beams of bulb angle cross section and adapted to lie alongside the longitudinal wooden sills of a car, means uniting said beams to each other, and a pair of draft gear supporting plates rigidly united to said beams through the horizontal flanges of the latter, and angular rolled metal shapes secured to the upper portions of said plates, the forward ends of said rolled metal shapes being stepped down to provide a seat for an end sill and a buffer block, substantially as described.
- 15 3. In a device of the class described, the combination of a pair of longitudinally extending rolled metal beams of bulb angle shape, a vertical web uniting said beams at

their forward ends, and a horizontal web uniting the same at a point near their rear end, a pair of cast metal draft gear supporting plates rigidly secured to said beams through the horizontal flanges of the castings and beams, and rolled metal angles secured to the upper and lower edges of said castings, the upper of said angles providing a horizontal flange adapted to lie beneath a wooden center sill, the forward ends of said upper angles providing a seat for a car end sill, substantially as described. 30

Signed at Chicago, Illinois, this 22d day of November, 1915.

WILLIAM S. TROWBRIDGE.
